UNITED STATES PATENT OFFICE.

GEORGE P. BUMP, OF LA CROSSE, WISCONSIN.

COMPRESSED-AIR STARTING APPARATUS.

1,294,870.

Specification of Letters Patent. Patented Feb. 18, 1919.

Application filed November 16, 1915, Serial No. 61,794. Renewed August 15, 1918. Serial No. 250,081.

To all whom it may concern:

Be it known that I, GEORGE P. BUMP, a citizen of the United States, residing at La Crosse, Wisconsin, have invented certain new and useful Improvements in Compressed-Air Starting Apparatus, of which the following is a specification.

My invention is intended for starting oil or gas engines such as used in automobiles or used in stationary plants by compressed air and for compressing the air used for the purpose stated, the same unit employed for compressing the air being used as the motor element in starting the engine by the manipulation of certain controlling means by the operator.

The said unit when acting as an air compressor is driven by the momentum of the car or by the engine just before coming to a state of rest the power thus derived being sufficient to drive the unit now acting as a compressor to store air under proper compression to be used in starting the machine.

The invention consists in the features and combination and arrangement of parts hereinafter described and pointed out in the claims.

In the accompanying drawings:

Figure 1 is a sectional plan view of an apparatus embodying the invention.

Fig. 2 is a side view partly in section of Fig. 1.

Fig. 2^a is a detail view of a controlling valve.

Fig. 3 is a side view of the air compressing and motor element with one of the heads removed to show the interior parts, this view being taken from the left of Fig. 1.

Fig. 4 is an inside view of port bed looking from the opposite direction from the view of Fig. 3.

Fig. 5 is a side view of the clutch mechanism.

Fig. 6 is a sectional view of the controlling ports and frame work.

Fig. 7 is a vertical section of the controlling valve mechanism at right angles to Fig. 2.

The air compressing and motor unit A comprises a structure similar as to its main parts to that shown in an application for Letters Patent of the United States, filed by me November 16, 1915, Serial Number 61,793.

It comprises two pistons 1, 2 each of segmental form rotating in cylinders 4, 5,

which intersect each other, the paths of the pistons consequently intersecting. The air intake port is shown at 34 and the exhaust ports at 38, 39, said ports being provided with check valves. The pistons are geared together by the gears 9, 10 on their shafts 7, 8, which are parallel with each other and are mounted in the casing. When the pistons are driven to act as air compressors the air is compressed between the horn or end portion of one piston and the cylindrical face of the other piston and is discharged through the valved outlet port. For instance as shown in Fig. 3, the air is being compressed in the space *a* and is being discharged through the port 38 and its check valve. During this time a fresh charge of air is being drawn in through the intake into the space 4 for subsequent compression. As the rotation continues the charge which has been drawn into the space 5 will be compressed between the horn *c* of piston 2 and the cylindrical side of piston 1 and discharge of this air will take place through the exhaust port 39 and its check valve.

It will thus be seen that compressed air is delivered first from one of the cylinders and then the other through their respective ports 38, 39 when the pistons are rotated in the arrow direction Fig. 3 and when suitable valve connections are properly adjusted. For driving the unit shown in Fig. 3 and comprising the two rotary pistons to act as air compressors one of the shafts viz. 7 is extended as shown in Fig. 1 and has keyed to its outer end a clutch disk 6 having pockets 12 containing clutch rollers 13 arranged to bear on the inner periphery of an encircling casing or drum 14 which finds a bearing on the outside of the boss 15 formed integrally with one side or head 16 of the casing. This drum is driven from the engine of the automobile or other part thereof by a chain 17 engaging a sprocket wheel 18 formed with or mounted on the drum. When the controlling lever of the automobile is thrown into position to stop the car, the chain through a suitable clutch, at the same time is operated so that the final portion of the motion of the car or of the engine may be utilized to operate the air pump as above described to store compressed air in a tank ready for use in starting the car.

The connection for conveying compressed air to and from the tank is shown at 19. It

connects with the casing of the pump or rather with the inlet and outlet ports thereof through a valve casing 20 containing a rotary controlling valve 21 having a passage 5 or conduit 22 and a port 23. The interior of the casing 20 connects with the inlet 34 and through the port 34^a and passage 34^x and with the two outlets 38, 39 by the port 38^a and passage 38^x common to both the latter ports. A pipe 24 leads from the casing 20 by a port 24^a. The rotary controller valve 21 is mounted upon a shaft 25 extending out through the casing and having an arm 26 by which the valve is operated. A spring 27 serves to hold the valve to its seat by pressing the valve shaft or stem longitudinally.

The rotary valve is shown in Fig. 2 in the position assumed by it when the compressed air is being delivered from the pressure tank in the direction of arrow α to the casing containing the pistons for making them act as motor elements for starting the car. When, however, the valve is given a quarter turn so that its conduit 22 connects the ports 24^a, 34^a and the valve port 23 connects with the outlet channel or port 38^a and supposing the shaft 7 is driven from the engine and the pistons 1, 2 rotated to act as an air compressing pump air at atmospheric pressure will be drawn in through the pipe 24, port 24^a, conduit 22, port 34^a, passage 34^x and inlet port 34 past the check valve located at said port and thus into the chamber 4 or 5, according to the relative positions of the segmental pistons 1 and 2 and the air which is compressed by said pistons, passes out through the port 38 or 39 as the case may be, through the passage 38^x, ports 38^a and 23 into the casing 20 and thence through the pipe 19 to the storage tank.

A check valve 27 is arranged between the casing 20 and the pipe 19, said valve finding a seat at 28 and closing toward the valve casing 20. When the rotary valve is turned 90° from the position shown in Fig. 2 in the direction of the arrow for storing air in the tank the check valve will be allowed to seat itself, being carried by a rod 29. The valve is pressed by a spring 31 on said rod 29. When now the air is sent to the tank the check valve will raise, its spring allowing this action, a charge of compressed air having passed the check valve into the pipe 19 and tank the check valve will close and hold this accumulated pressure ready for use.

A pipe 32 extends to a pressure gage by which the pressure in pipe 19 and the tank can be seen. When the pressure has reached 60 a certain amount a suitable clutch, not shown, may be thrown out of action to stop the driving action imparted through the sprocket chain 17 and this clutch can be operated automatically or manually. At 29^x

I show a finger connected to the rotary valve 65 at 30, which is adapted to lift the check valve when the rotary valve is turned to allow the compressed air to pass from the tank to the rotary unit A to drive the same as a motor in starting the engine. 70

Starting operation.

Air pressure having been accumulated in the tank through the medium of unit or element A acting as an air compressing pump and the apparatus having come to rest can be started by reversing the operations above mentioned and using the unit A as a motor to drive the chain 17 and thus start the engine. 80

For this purpose the operator through the lever 26 sets the rotary controlling valve in the position shown in Fig. 2, this same act resulting in lifting the check valve 27' from its seat and maintaining it in this position as long as the compressed air is to be allowed to enter the unit A to drive its pistons 1 and 2. The compressed air now passes from the tank through pipe 19 past check valve 27', into valve casing 20, thence through port 34^a, passage 34^x and port 34 into the chamber 4 or 5, as the case may be, thus rotating the pistons 1 and 2, the air after having done this passing out the outlet port 38 or 39, as the case may be, to the common passage 38^x, port 38^a, valve passage 22, port 24^x to atmosphere through pipe 24. 95

The pistons 1 and 2 in rotating drive shafts 7 and 8 these being geared together at 100 9, 10 and a pinion 33 on shaft 8 drives the gear 40 carried by a sleeve 41, turning loosely on the shaft 7. This sleeve has keyed to it at 42 a clutch disk 43 having pockets in which are seated clutch rollers 44, acting on the interior of the drum 14, this clutch disk being arranged alongside the clutch disk 6 before described. 105

The pockets 44^x as shown in dotted lines, Fig. 5, have their inclined bottoms so disposed that with the clutch disk rotating in the direction of the dotted arrow the clutch ball will drive the drum 14 in the proper direction to start the engine through the sprocket wheel 18 and chain 17. 110

I prefer to provide loose guide or controlling pieces 45 for the clutch balls or rollers so that the balls or rollers will be moved along the pocket. 115

It will be observed that the drum 14 being journaled on the rigid bearing 15 fixed to or forming an integral part of the frame and being connected to the shaft 7 through the clutches the pull of the chain 17 will not apply any side thrust to the shaft 7 and thus the pistons 1 and 2 will run true. 120

It will be observed that the pistons of the unit A whether air compressing is being

done or starting of the engine is being accomplished always rotate in the same direction.

While I have described that the air compressor is driven through connections, as the chain 17 from the engine, it will be understood that when the invention is used in connection with an automobile or the like, I do not limit myself to the use of a direct connection between the compressor and the engine of the automobile as power may be derived from some other moving part of the vehicle the momentum of the vehicle being utilized to afford the necessary power to drive the air compressor during a suitable period before the vehicle or engine comes to rest.

Having thus described my invention what I claim is:

20 1. In combination in a starting apparatus for engines, a unit having rotary means for compressing air and for acting as a motor to start the engine, said unit having inlet and exhaust ports, a storage tank for compressed air, a spring check valve for holding the pressure in the tank, said valve yielding to the air pressure passing to the tank, valve means for connecting the inlet port either with the atmosphere for the intake of air for compression or with the storage tank for the delivery of compressed air to the rotary means for driving it as a starting motor, said valve means connecting the exhaust port with the storage tank for the delivery of compressed air thereto or with the atmosphere for the discharge of the spent air and means for positively holding the check valve open when said valve means is operated for the delivery of compressed air to the rotary means for starting, substantially as described.

2. In combination in a starting apparatus for engines, a unit having rotary means for compressing air and for acting as a motor to start the engine, said unit having inlet and exhaust ports, a storage tank for compressed air, a check valve for holding the pressure in the tank, valve means for connecting the inlet port either with the atmosphere for the intake of air for compression or with the storage tank for the delivery of compressed air to the rotary means for driving it as a starting motor, said valve means connecting the exhaust port either with the storage tank for the delivery of compressed air thereto or with the atmosphere for the discharge of the spent air and means for holding the check valve open for the delivery of compressed air to the rotary means for starting, said check valve being operated automatically when the valve means is operated, and operating independently of the said valve means during the pumping action, substantially as described.

3. In combination in a starting apparatus

for engines, a unit having rotary means for compressing air and for acting as a motor to start the engine, said unit having inlet and exhaust ports, a storage tank for compressed air, a check valve for holding the pressure in the tank, main valve means for connecting the inlet port either with the atmosphere for the intake of air for compression or with the storage tank for the delivery of compressed air to the rotary means for driving it as a starting motor, said valve means connecting the exhaust port either with the storage tank for the delivery of compressed air thereto or with the atmosphere for the discharge of the spent air and means for holding the check valve open for the delivery of compressed air to the rotary means for starting, said check valve being operated automatically when the valve means is operated, by a connection extending from said valve means, said check valve having movement independent of the main valve under the pressure of the pumped air, substantially as described.

4. In combination in a starting apparatus for engines, a unit having rotary means for compressing air and for acting as a motor to start the engine, said unit having inlet and exhaust ports, a storage tank for compressed air, a check valve for holding the pressure in the tank, valve means for connecting the inlet port either with the atmosphere for the intake of air for compression or with the storage tank for the delivery of compressed air to the rotary means for driving it as a starting motor, said valve means connecting the exhaust port with the storage tank for the delivery of compressed air thereto or with the atmosphere for the discharge of the spent air and means for holding the check valve open for the delivery of compressed air to the rotary means for starting, said valve means comprising a rotary member having ports and an arm connected with said rotary member for operating the check valve, said check valve having movement independent of said arm to open during pumping of the air to the tank.

5. In combination in an engine starting apparatus a casing having intersecting cylinder spaces therein, pistons arranged opposite each other in said spaces, parallel shafts carrying said pistons, gearing between the shafts, a clutch member mounted on one of the shafts, a gear loosely mounted on said shaft and meshing with a gear on the shaft of the other piston, a clutch member connected with said loose gear, power transmitting connections and clutch means between said clutch members and said power transmitting connections, substantially as described.

6. In combination in apparatus of the class described a casing having intersecting cylinder spaces, pistons rotatable in said

4
cylinder spaces, inlet and outlet ports for the casing, a storage tank for compressed air, valve means for connecting the casing with the storage tank either for charging the 5 same or for delivering compressed air to the casing, parallel shafts carrying the pistons, gearing between the said parallel shafts, a bearing on the casing through which one of the shafts extends, a gear having a sleeve 10 extending through said bearing and rotatable about the said shaft, a pinion on the other shaft meshing with said loose gear, a clutch drum mounted on the exterior of said bearing, power transmitting means connected 15 with said clutch drum and clutch means between the said drum and the said sleeve and the shaft within the sleeve, substantially as described.

7. In combination in apparatus of the 20 class described, a casing having intersecting cylinder spaces therein, segmental pistons rotatable in said spaces, parallel shafts carrying the said pistons, inlet and outlet ports for the casing, gearing between the shafts, a bearing on the casing through which one of the shafts extends, a sleeve rotatable about the shaft and extending through the said bearing, a gear connected with the sleeve, a pinion on the other piston shaft and meshing 25 with said gear on the loose sleeve, a clutch drum mounted on the outside of said bearing, clutch disks connected respectively with the loose sleeve and the shaft extending through said sleeve, said clutch disks having pockets and clutch members in said 30 pockets engaging the interior of the clutch drum, substantially as described.

8. In combination a casing, a pair of rotary pistons therein having intersecting 35 paths and adapted to act either as motors or as air compressing and pumping means, parallel shafts carrying said pistons, a compressed air tank, valve mechanism between

the same and the casing to deliver air to the 45 tank when the pistons act as air compressing and pumping means and to deliver air from the tank to the casing when the pistons act as motors, gearing between the parallel shafts to rotate one from the other, clutch means connected to one of the shafts for 50 driving the pistons for compressing and pumping the air and clutch means connected to the other shaft for transmitting power therefrom when the pistons act as motors, said pistons rotating in the same direction 55 both when acting as a pump and as a motor, substantially as described.

9. In combination, a casing, a pair of rotary pistons therein having intersecting paths and adapted to act either as motors 60 or as air compressing and pumping means, parallel shafts carrying said pistons, a compressed air tank, valve mechanism between the same and the casing to deliver air to the tank from the pumping pistons and to deliver air from the tank to the pistons acting as motors, gearing between the parallel shafts to rotate one from the other, clutch means connected to one of the shafts for 65 driving the pistons as a pump and clutch 70 means connected to the other shaft for transmitting power therefrom when the pistons act as motors, said pistons rotating in the same direction, both when acting as a pump and as a motor and said clutches operating 75 automatically in releasing or clutching and driving and in opposite directions rotatively in respect to each other, substantially as described.

In testimony whereof, I affix my signature in presence of two witnesses.

GEORGE P. BUMP.
